UNITED STATES PATENT OFFICE.

CARL KRAETSCH, OF DES MOINES, IOWA.

GOLF-PRACTICE DEVICE.

Application filed March 3, 1926. Serial No. 91,991.

The object of my invention is to provide a golf practice device involving structure whereby the various conditions of the game may be simulated.

More particularly, it is my object to provide such a device having various parts so arranged that golf practice may be carried on in such manner as to afford conditions for driving similar to those on a golf course, and to provide means for checking the results of the plays, according to the effectiveness, force, height, and lateral flight of the ball.

With these and other objects in view, my invention consists in the construction, arrangement and combination of the various parts of my golf practice device, whereby the objects contemplated are attained, as hereinafter more fully set forth, pointed out in my claims, and illustrated in the accompanying drawings, in which:

Figure 1 is a front elevation of my golf practice device.

Figure 2 is a detail, sectional view taken on the line 2—2 of Figure 1.

Figure 3 is a horizontal, sectional view taken on the line 3—3 of Figure 2; and

Figure 4 is a detail view of part of the impact mechanism and a sectional view of one of the pockets involving an important feature of my device.

Various golf practice devices have failed to give the desired satisfaction, because they did not simulate to a sufficient degree the conditions under which golf games are played on an actual course, and they failed to record enough of the result of driving a ball.

It is therefore my purpose to provide in an indoor practice device in a room suitable for the purpose a series of pockets, the mouths of which are arranged in planes curved from side to side and from top to bottom. These pockets are arranged with their axes in lines converging toward a common point, so that the balls may be driven into the pockets with a minimum likelihood of striking the sides thereof.

At the back of each pocket is an impact device for registering the force of the ball in its flight.

By this arrangement also, the sidewise flight of the ball can be taken into consideration to simulate the results when a ball on the course is driven to the right or left from the central line down the fairway.

I have provided also a curtain, which can be moved to position in front of the pockets or away from such position. On this curtain may be thrown a series of pictures representing portions of a golf course. Thus it is possible just before the ball is driven, to throw on the screen or curtain a picture of the portion of the course upon which the players may be assumed to be playing.

In the accompanying drawings, I have used the reference character 10 to indicate generally the side walls of the device, which may be the side walls of a room or otherwise as desired. These walls may be made of any suitable material, such as wallboard, metal, canvas or otherwise, as may be suitable and desirable under the circumstances.

I have also shown over the front part of the device a top or ceiling member 11 for protecting the ceiling of the room, where the device is installed, against balls which may be driven almost directly upward.

At the front of the device, I have arranged a small, flat, low platform or the like 12, which will serve as the usual tee, on which the ball 13 may be placed for playing.

Adjacent to the tee 12 is a small space 14, which may have any desired outline, but is shown rectangular, having a long fiber rug or the like 15, simulating the "rough" of a golf course.

In front of the tee and what I will for convenience call the "rough" space 15 is a larger area 16, comprising a box or container, having sand 17 therein, thus simulating another condition, which may be found on a golf course.

The main portion of the floor 18 may be covered with a fiber rug to simulate the grass course.

Adjacent to the "rough" 15, I place a projection lantern 19 for throwing images on the curtain hereinafter referred to.

At the back of the "course", I arrange a series of pockets 20, having the mouths 21 and the walls 22, converging toward each other toward the rear.

These pockets are arranged in lines or in a plane curved from side to side, as shown in Figure 3, and also in lines or in a plane curved from top to bottom, as shown in Figure 2. They are thus so arranged that the lines of their axes converge toward a common point.

With this arrangement, the golf balls can

be driven into the pockets with the least likelihood of striking the side walls thereof or of having their momentum destroyed by the impact on the side walls.

5 The pockets 20 may be made of any suitable material, for example, thin fiber may be used, and the pockets may be mounted on cross rods 24.

Referring to Figure 4, it will be noted that 10 at the back of each pocket is a closure comprising four closure elements 25, hinged as at 26 and 27 on brackets 28 and 29 on the outside of the pockets 20.

The closure elements 25 are normally, 15 yieldingly held closed by resilient members 30 connected thereto and to the brackets 29, as shown in Figure 4. This arrangement of the closure elements is such that when the ball strikes the closure elements at the 20 back of the pocket, they will be swung to open position, as shown in dotted lines in Figure 4, to allow the escape of the ball, and will then automatically return to closed position.

25 These closure elements 25 also help to slightly guide the ball to make it strike the impact device 31.

One of these impact devices is yieldably mounted in the rear of each pocket on a 30 rod 32 slidably mounted on supports 33 and 34 and yieldably held by a spring 35 at the forward limit of its movement.

These impact devices may be connected 35 with registering means not here shown for thus registering the impact of each ball.

In this connection, it may be mentioned 40 that these impact registering means, when employed, may be so arranged that when the ball is given just the desired direction, it will go into certain pockets and register on said impact devices for registering for instance the equivalent of a two hundred yard drive.

If the ball goes too high or too low, it 45 can be made to register the equivalent of a less distance.

Likewise, if it goes into the side pockets, it will register greater or less distance according to the height of the pocket, which it 50 enters.

For further stimulating interest in the game flexible curtains 36 and 37 are mounted on rollers 38 and 39 in casings 40 and 41 near the bottom and top of the pockets. The 55 free edges of the curtains or screen members 36 and 37 are mounted on rods or the like 42, which travel in curved guide slots 43.

Connected with the rod 2 is a rope or the like 44, extending over a pulley 45 located 60 at such a point as to properly guide the curtain or screen 36 for moving it to open position, and thence over a guide or the like 46 to position near the tee.

A flexible device 47 is connected with the 65 rod 42 of the upper screen 37 and is thence

extended around the pulley 48, and is then connected to the flexible member 44, so that the movement of the flexible member 44, when it is pulled over the guide 46 will open both curtains or screens. The rollers 38 and 39 are spring actuated to tend to wind them up.

In the practical use of my golf practice device, the player puts his ball on the tee 12, using the small sand or other tee.

Another person operates the rope or flexible device 44 for pulling the screens to open position. The lantern 19 is used to then throw on the screen a picture of the portion of some golf course, showing it as it would be visible from where the ball lies. This gives the player a visible representation of the course, and when the rope 44 is released, he can drive with that representation in his mind.

Insomuch as good golf requires that the attention be entirely centered on the ball for an instant before driving, it is obvious that the removal of the picture is not substantially detrimental to the player's game.

The ball is driven and passes into and through one of the pockets and strikes against one of the impact devices 31. The particular vertical tier of pockets will register the distance of the flight of the ball to the right or left of the proper line.

It is to be understood that the game is to be played with a chart (which indicates a hole on a golf course), laid out to scale, composing a driving tee, fairway, "rough", sand bunkers, and a putting green with a four inch hole in the center.

Thus for example, the ball is placed on the tee 12 (Figure 3), and is driven, and it goes through a pocket 20, behind which is a registering device, which registers the distance that the ball would travel (say 175 yards). It also registers what vertical tier of pockets the ball passes through (say second to the left of the center).

Then to secure the score, it is necessary to turn to the chart, and track a line straight 175 yards, which indicates the distance the ball travels, and then at right angles to the left ten yards (as each vertical tier indicates the distance out of line the ball travels) and make a cross on the score chart.

Then if this location on the score chart is noted thereon as "fairway", the next shot is taken from off the same tee, but should this location of the ball denote on the chart that the ball is in the "rough", the next shot must be played from the long fiber rug 15, which denotes "rough", or should the location of the ball on the chart show that the ball fell into a sand bunker, the next shot should be played from the sand plot 16.

In like manner, each succeeding shot must be made until the ball is shown to rest on the putting green as noted on the chart.

If the game is properly scored on this chart, the distance of the ball from the hole is shown, say 6 feet, for example. The hole 100 and putting green 101 are shown in 5 Figure 3.

Now the ball is placed 6 feet from the hole on the putting green, and the number of strokes it takes to put the ball in the hole, plus the number of strokes it took previously to get from the tee to the green is 10 your score for this hole.

Charts should be numbered similar to the holes on a regular golf course, thus chart 15 No. 1, is hole No. 1, and so forth. Each chart should be different in regard to distance from tee to putting green, lay of the course, in regard to the "roughs", bunkers and other hazards.

It will be seen from the foregoing illustration that with my practice device, the 20 game can be played under conditions which gives it unusual interest for practice devices, because of the fact that playing conditions are simulated so closely.

25 Modifications may be made in the details of structure and of the playing rules under which the game is played without departing from the real spirit and purpose of my invention, and it is my intention to cover by 30 my claims, any modified forms of structure or use of mechanical equivalents, which may be included within the scope of such claims.

I claim as my invention:

35 1. In a device of the class described, a series of pockets with walls converging from their mouths, arranged in vertical and horizontal rows, with the lines of their axes converging toward a common distant point.

40 2. In a device of the class described, a series of pockets with walls converging from their mouths, arranged in vertical and horizontal rows, with the lines of their axes converging toward a common distant point, and independent impact devices adjacent to 45 the bottoms of the respective pockets.

50 3. In a device of the class described, a series of pockets with walls converging from their mouths, arranged in vertical and horizontal rows, with the lines of their axes converging toward a common distant point, and a curtain adjustable in a curved plane 55 in front of said pockets.

55 4. In a device of the class described, a series of pockets with walls converging from their mouths, arranged in vertical and horizontal rows, with the lines of their axes converging toward a common distant point, and yielding closure elements for the pockets.

60 5. In a device of the class described, a series of pockets arranged in a group with their axes in lines converging toward a common point, yielding closure elements for the bottoms of the pockets, and impact receiving means adjacent to the bottoms of 65 the pockets.

6. In a device of the class described, a series of pockets arranged in a group with their axes in lines converging toward a common point, yielding closure elements for the bottoms of the pockets, and independent impact receiving devices arranged adjacent to the bottoms of the respective pockets. 70

7. In a device of the class described, a series of pockets, with walls converging from their mouths, arranged in vertical and horizontal rows with the lines of their axes converging toward a common distant point, the mouths of said pockets being arranged in lines curved from side to side. 75

8. In a device of the class described, a series of pockets, with walls converging from their mouths, arranged in vertical and horizontal rows with the lines of their axes converging toward a common distant point, the mouths of said pockets being arranged in lines curved from top to bottom of the rows. 80

9. In a device of the class described, a series of pockets, with walls converging from their mouths, arranged in vertical and horizontal rows with the lines of their axes converging toward a common distant point, the mouths of said pockets being arranged in lines curved from side to side and from top to bottom of the rows. 85

10. In a device of the class described, a series of pockets, with flexible fabric walls converging from their mouths, arranged in vertical and horizontal rows, with the lines of their axes converging toward a common distant point. 100

11. In a device of the class described, a series of pockets arranged in a group with their axes in lines converging toward a common point, and yielding closure elements for the bottoms of the pockets, comprising hinged members, and means for yieldably holding such hinged members in closing position. 105

12. In a device of the class described, a series of pockets arranged in a group with their axes in lines converging toward a common point, and yielding closure elements for the bottoms of the pockets, comprising hinged members, and means for yieldably holding such hinged members in closing position, said hinged members being normally inclined from their rear edges forwardly and away from each other. 110

13. In a golf practice device, a floor having different parts arranged to simulate parts of a golf course, for providing variety of practice in driving a golf ball, and a series of pockets for receiving a ball driven from such floor arranged with the lines of their axes converging, and means for throwing on a curtain immediately in front of said pockets, a picture of a portion of a golf course. 125

14. In a golf practice device, a floor hav- 130

ing different parts arranged to simulate parts of a golf course, for providing variety of practice in driving a golf ball, a series of pockets for receiving a ball driven from such floor arranged with the lines of their axes converging, impact means for stopping driven balls, and means for throwing on a curtain immediately in front of said pockets a picture of part of a golf course.

10. 15. In a golf practice device, a floor hav-

ing different parts arranged to simulate parts of a golf course, for providing variety of practice in driving a golf ball, a series of pockets for receiving a ball driven from such floor, a curtain adjustable to and from position immediately in front of said pockets, and means for throwing on said curtain a picture of part of a golf course.

15. Des Moines, Iowa, February 19, 1926.

CARL KRAETSCH.
